FRANCE.

INTERNAL-COMBUSTION ENGINE.

1,105,454

Specification of Letters Patent. Patented July 28, 1914.

Application filed October 27, 1913. Serial No. 797,546.

To all whom it may concern:

Be it known that we, PIERRE PICTET, a citizen of the Helvetic Confederacy, and resident of Geneva, Switzerland, and MARCEL VERNAZ, a citizen of the French Republic, and resident of Annemasse, Haute Savoie, France, have invented certain new and useful Improvements in Internal-Combustion Engines, of which the following is a specification.

This invention relates to internal combustion engines.

The object of the invention is to provide improved means for admitting and exhausting the gas.

A further object of the invention is to provide in an internal combustion engine a working piston and a distributing piston and means coöperating therewith to control the inlet and outlet of the gases.

The invention also comprehends improvements in the details of construction and arrangement of parts which will be herein-after described and particularly pointed out in the claims.

In the drawings: Figure 1 is a vertical section of the upper portion of one cylinder of our improved engine. Fig. 2 is a cross section of the same on the line A--B of Fig. 1. Fig. 3 is a similar view on the line C--D of Fig. 1. Fig. 4 is a diagrammatic view illustrating the position of the parts when the exhaust port is open. Fig. 5 is a similar view illustrating the position of the parts when introducing a charge. Fig. 6 is a similar view, the ports being closed. Fig. 7 is a similar view, the parts being in position to compress the charge. Fig. 8 is a similar view, the charge having been fired. Fig. 9 is a similar view, the parts being in position to just open the exhaust port. Fig. 10 is a detail vertical section of a modified form of the improvement. Fig. 11 is a similar view of another modified form of the invention.

e indicates a cylinder, in the lower part of which operates what we term the working piston *m*, connected by a connecting rod *n*, with a crank *p*, of a shaft *o*. In the upper part of the cylinder operates what we term a distributing piston *g*, which has a partition *h*, forming the upper part of the combustion chamber in the cylinder. The dis-

tributing piston *g*, is provided with an annular recess *g'*, and confined in this recess and operating on the inner surface of the cylinder, is a resilient ring *b*, which is shorter than the length of the annular recess, for a purpose to be described. Below the partition *h*, and registering with the interior of the distributing piston and the annular recess *g'*, is an inlet port *a*, which at the proper time, is designed to register with an inlet port *c*, in the cylinder *e*. Also formed in the cylinder, below the plane of the inlet port *c*, is an exhaust port *f*. The exhaust port is controlled by the distributing piston. When the distributing piston is near its limit of upward movement the exhaust port is opened for the escape of the burnt gases in the cylinder and upon the next succeeding down-stroke of said piston, said port is closed. The distributing piston *g* is provided with packing rings *d*, to prevent escape of the gases, when the engine is operated. The distributing piston is connected at *i* by a connecting rod *k*, with the crank *j* of a shaft *l*.

In operation, shaft *o* revolves twice to one revolution of the shaft *l*, so as to properly time the movements of the two pistons. Assume the parts to be in the position shown in Fig. 4, that is, the exhaust port is wide open and the burnt gases are being exhausted by the upward movement of the working piston *m*, while the distributing piston is just about ready to descend. Upon further movement of the shafts *o* and *l*, the burnt gases will be exhausted before the distributing piston will cover the exhaust port, and the working piston which travels faster than the distributing piston also moves down, the distributing piston following. During the first part of the downward movement of the distributing piston, the ring *b*, which frictionally engages the wall of the cylinder will remain stationary, hence the port *a* will communicate with port *c* and a charge will be admitted, and port *f* will be closed. Continued movement of the distributing piston will carry with it the ring *b*, shown in Fig. 5, and as the working piston *m* is traveling down a charge is being drawn into the cylinder. Continued movement of the parts will bring the pistons to the positions shown in Fig. 6, that is, the work-

ing piston has descended as far as it can go, while the distributing piston will descend farther. Upon the crank passing the dead center, the piston *m* starts up, and in 5 time, piston *g* also starts to ascend, but of course, slower than the movement of piston *m*, hence the charge is compressed. As shown in Fig. 7, it will be seen that when the pistons are in the positions just described 10 that the charge will be compressed as stated. At this point it is to be noted that when the distributing piston starts to rise, the bottom wall of the recess engages the bottom of the ring *b*, hence the latter 15 acts to close the inlet port *a*, as clearly shown in Fig. 7. The charge becomes compressed and is fired by the spark plug *q*, then the working piston *m* again commences to descend, while the distributing piston continues 20 to rise, the inlet ports *a* and *c* being closed during this period, as shown in Fig. 8. At the time the working piston *m* reaches its lower point the bottom of the distributing piston uncovers the exhaust 25 port *f*, as shown in Fig. 9, so that immediately the piston *m* commences to rise, the burnt gases will be exhausted, the distributing piston continuing to rise to fully open the port, as shown in Fig. 4. In Fig. 11, 30 two cylinders *r* and *s* are shown, same being connected at the top by a passage *r'*. The distributing piston operates in the cylinder *r*, and is constructed substantially the same as that previously described, except 35 that it is inverted, which of course, necessitates inverting the inlet and outlet ports *c* and *f*, and the connecting rod *h* is attached to the bottom of the partition *h*. The working piston operates in the cylinder *s*. Obviously, 40 precisely the same results will flow from this construction, and where it is impossible to install an engine such as shown in Fig. 1, owing to lack of space, substantially the same result can be obtained by 45 employing such a construction as shown in Fig. 10. In Fig. 11 is shown a construction wherein the cylinder *n* in which the working piston *m* operates, is of larger diameter than the cylinder *t*, in which the distributing piston operates. The cylinders *n* and *t* 50 may be integral, or separate and bolted together.

What we claim is:—

1. In an internal combustion engine, the combination of a cylinder formed with an inlet and an outlet port, a working piston operating in the cylinder, a hollow distributing piston operating in the cylinder, said distributing piston having a partition and 55 an inlet port below the partition, the outer periphery of the distributing piston having a recess with which the inlet port in said piston registers, a slid- 60 able element fitting in the recess and bearing against the

inner wall of the cylinder, the said element 65 being of less length than the length of the recess, means for reciprocating the distributing piston, and means for reciprocating the working piston faster than the distributing piston, whereby when the distributing 70 piston descends, the slid- able element will be frictionally held against the wall of the cylinder and uncover the inlet port in said piston and will be subsequently moved by said piston and a charge will be admitted 75 and will be compressed between said two pistons.

2. In an internal combustion engine the combination of a cylinder formed with an inlet and an outlet port, a working piston operating in the cylinder, a hollow distributing piston operating in the cylinder, said distributing piston having a partition and an inlet port formed at one side of the partition, the outer periphery of the distributing piston having a recess with which the inlet port registers, a slid- able element fitting in the recess and bearing against the inner wall of the cylinder, the said element 80 being of less length than the length of the recess, means for reciprocating the distributing piston, and means for reciprocating the working piston faster than the distributing piston, whereby when the distributing 85 piston moves in one direction the slid- able element will be frictionally held against the wall of the cylinder and uncover the inlet port in said piston and will be subsequently moved by said piston and a charge will be admitted 90 and will be compressed between said two pistons.

3. In an internal combustion engine, the combination of a cylinder formed with inlet and outlet ports, a working piston operating in the cylinder, a hollow distributing piston having a partition and formed with an inlet port below said partition, a slid- able sleeve operating in a recess formed between the piston and the cylinder, the sleeve being 105 of less length than the recess, and the sleeve 110 being in frictional engagement with the cylinder, means for reciprocating the distributing piston, and means for reciprocating the working piston faster than the distributing piston, whereby when the distributing 115 piston descends the sleeve will be frictionally held against the wall of the cylinder and uncover the inlet port in said piston and will be subsequently moved by said piston and a charge will be admitted and 120 will be compressed between said two pistons.

4. In an internal combustion engine, the combination of a cylinder formed with inlet and outlet ports, a working piston operating in the cylinder, a hollow distributing 125 piston having a partition and operating in the cylinder and formed with an inlet port below said partition and adapted to regis-

ter with the inlet port in the cylinder, means mounted on and operated by the distributing piston to open the inlet ports on one stroke and close said inlet ports on the next 5 succeeding stroke, the said latter means including a slide valve, frictionally held against the cylinder until moved by the distributing piston, means for operating said distributing piston, and means for operating the working piston twice as fast as said distributing piston.

In testimony whereof we have hereunto set our hands in presence of two witnesses.
